His Attorney.

UNITED STATES PATENT OFFICE.

FRED HUFNAGEL, OF ST. LOUIS, MISSOURI.

DUSTGUARD.

Application filed June 4, 1921. Serial No. 475,175.

To all whom it may concern:

Be it known that I, FRED HUFNAGEL, a citizen of the United States, residing at the city of St. Louis, in the State of Missouri, have invented certain new and useful Improvements in Dustguards, of which the following is a specification.

This invention is intended to prevent dust from settling on exposed parts of an overhead-valve motor. It not only saves considerable time and a great deal of labor heretofore expended in cleaning the parts, but also saves them from wearing out and the expense of putting in new ones, and, also, eliminates a great deal of noise, as it makes a more compact compartment and does away with the loose contact of parts worn on account of dust.

This dustguard is preferably of tin, but any suitable material may be used. One advantage of using tin is that it can easily be bent to the necessary form. The various plates shown in the drawings and herein described are so located, shaped, and fastened that they not only inclose all exterior moving parts of an overhead-valve engine, but in addition prevent access of dust thereto, which prevents dust from sifting within the said inclosure and settling upon the said parts. The object is, not only to insure better action of the parts that arises from freedom from dust but, also, to prevent the greater wear and tear that the presence of dust produces. Not only does the presence of dust increase friction and wear but, also, it mixes with any oil present and gums the parts and retards their action.

In general this invention is a tight fitting casing neatly inclosing the sides and top of the engine-block and connected parts. It is not a mere box, as such a box would be loose and rattle. One thing highly undesirable in a motor is any kind of noise. Therefore, this casing is formed of a plurality of plates that closely fit and are tightly fastened to the engine at the different points where certain of its parts are exposed to the settling of dust. In such a construction it is necessary to provide not only for tight attachment, but, also, for easy removal of most of the parts constituting the casing, so as to permit oiling and adjustment of the parts that are covered thereby, and, also, access thereto for the purpose of repairs, replacements, or the like.

In the accompanying drawings forming part of this specification, in which like num-

bers of reference denote like parts wherever they occur,

Figure 1 is the front side elevation of a motor with the dustcaps or guards of the present invention, some of the guard sections or covers being removed;

Figure 2 is a top plan view of an engine with the said caps in place;

Figure 3 is a section taken on the line 3—3 in Figure 1, showing the insulation of the sparkplugs; and

Figure 4 is a detail of the base connection of the dustcap to the engine-block, taken on the line 4—4 in Figure 1.

The cam-shaft 1 passes through a casting 2, to which casting is fastened a bent piece of metal 3 containing a deep groove 4, which piece of metal or bent plate 3 is attached to the casting 2 by bolts 5.

The plate 3 is formed with a base-part that rests upon the crank-case and two vertically up-turned parts 6 and 7. The part 6 is lower than and in front of the part 7. The bolt 5 passes through a slot 8 in plate 9 and through an opening 10 in member 7 and into casting 2, thereby fastening plate 7 and with it member 3 and plate 6 to casting 2. A plate 9 has its lower end inserted in the groove 4, and its upper end secured at 85 its edges to the adjoining angle-members 24 by means of bolts or other suitable fastening means. The slots 8, when plate 9 is in place, straddle the bolts 5, and the lower part of the said plate 9 fits into groove 4, as 90 clearly shown in Figure 4. Plate 9 has a rectangular opening 11, at the side and bottom edges of which are outwardly-projecting lips 43, secured to the outside of plate 9 by soldering on their outer periphery 44, 95 the inner periphery 45 of the said lips being separated from the said plate 9 to form a groove 46 in which slidably fits a door or cover-plate 47, which normally closes opening 11 in plate 9 and normally covers from 100 dust the valve-lifters 12. Without this invention the same are exposed to dust. With plate 47 in place they are covered therefrom. Where it is desired to oil them it is an easy matter to raise plate 47 from the position 105 shown on the left-hand in Figure 1 and to leave the opening 11 shown on the right-hand in Figure 1. A lifter or handle or knob 13 makes raising or lowering of plate 47 easy.

As the sparkplugs 14 are located under the center of the front sidewall of the en-

gine-block 15, between the valve-lifter rods 12 it is necessary to insert insulation (preferably in the form of a film-block) 16 to prevent short circuiting. This block of insulation 16 is fastened by means of small L-shaped metal plates 17 or plates shaped like angle-irons, which overlap ends of fiber block 16, the said plates 17 being attached by thumbnuts 18 and bolts 20 to the front plates 21; the plate 21 having a bend 22 to accommodate a nut 23 on bolt 20.

The end plates 48 on both sides of the engine-block are held in place by angle-members 24, which are located at the front 15 and back, and the lower parts of which extend below the center of the engine-block 15 to the piston walls, the top of the said members 24 extending high enough to clear the valve-springs 25 and the rocker arms 26.

20 A plurality of bolts and nuts counter-sunk and bolted fasten the members 24 and plates 48 together.

The rear-plate 27 forms the back of the casing and has a bent-iron plate or bracket 28 riveted at 30 to the same about at its center and extending up and down. The said plate 27 is fastened by one of the engine-head bolts 29 running through the said bent-iron plate or bracket 28. The rear 30 plate 27 is fastened, also, by means of countersunk bolts and nuts to the inside of the angle-members 24.

The edges of plates 27 and 48 overlap the flanges of angle-members 24 on the inside. 35 Plates 21 at their lower edges are provided with angular edges 32, and are fastened in place by the said edges fitting into a groove 33 in plate 9, and the said plates 21 are furthermore fastened in place to perpendicular extensions 34 of end-plates 48 by a thumbnut and bolt 35 at the top on each side. Plates 48 are fitted tightly against the crank case 49 at the bottom, thus forming a solid compartment or inclosure at the 40 lower end, thereby obviating rattling noises.

45 The lower fore-plate 9 need never be removed after having once been put in place, because opening 11 therein is about six inches long by one and one-half inches high, thus permitting oiling whenever necessary of the valve-lifters 12.

Opening 11 is guarded with a five-eighth inch wide vertical metal plate or strap 50 for the purpose of preventing plate or shutter 47 from slipping back and coming into contact with the valve-lifters 12 in case of

the said plate 47 accidentally getting out of position. The top-plate 38 is provided with a flange 39 and a handle 40, the said flange 39 overlapping the front-plates or fore-plates 21 and rear plate 27 and end-plates 48, the said overlapping excluding dust. The top-plate 38 is fastened in place by thumbnuts and bolts 42 on each side thereof, the said bolts being secured to the end-plates 48 and passing through the flange 39.

Having thus described this invention, I hereby reserve the benefit of all changes in form, arrangement, order, or use of parts, as it is evident that many minor changes 70 may be made therein without departing from the spirit of this invention or the scope of the following claims.

I claim:

1. A dustproof box for internal combustion engines comprising a plurality of plates suitably fastened together, said plates consisting of a top plate, a pair of side plates, rear and front plates, the said top plate provided with a flange overlapping the side 75 plates and rear and front plates, said side plates being held in assembled position by angle members and interfitting means engageable with said rear plates, said front plates comprising upper and lower members, 80 said lower member provided with an opening, and a movable plate adapted adjustably to close said opening, and means for securing said lower plates in position.

2. A dustproof box for internal combustion engines comprising a casting, said casting secured to a metallic base plate, said base plate having vertically upturned members, one of said members being lower and in front of the other upturned member, a 90 lower front plate provided with an opening, and with slots and having its lower end inserted between said upturned members, bolts passing through said slots and opening in said upturned member, side wall plates held 95 in position by angle members secured by bolts, rear plates secured to the engine head and overlapping said side plates and fastened thereto, top plates provided with flanges, said flanges overlapping said side 100 walls and rear plates and front plates and fastened thereto, and means securing said top plates in position.

In testimony whereof I hereunto affix my signature.

FRED HUFNAGEL.
